CLAIM

The ornamental design for a beverage container, as shown and described.

DESCRIPTION

FIG. 1 is a perspective view of a beverage container showing my new design;

FIG. 2 is a front elevational view thereof; the rear elevational view, the left and right side elevational views being identical;

FIG. 3 is a top plan view thereof; and,

FIG. 4 is a bottom plan view thereof.

The broken lines in the drawings illustrate portions of the beverage container that form no part of the claimed design.

1 Claim, 3 Drawing Sheets
